UNITED STATES PATENT OFFICE.

THEODORE G. LINDERME, OF DETROIT, MICHIGAN.

BOTTLE-COVER-PLACING MACHINE.

1,252,460.

Specification of Letters Patent.

Patented Jan. 8, 1918.

Application filed June 2, 1916. Serial No. 101,226.

To all whom it may concern:

Be it known that I, THEODORE G. LINDERME, a citizen of the United States of America, residing at Detroit, in the county 5 of Wayne and State of Michigan, have invented certain new and useful Improvements in Bottle-Cover-Placing Machines, of which the following is a specification, reference being had therein to the accompanying drawings.

This invention relates to a bottle cover placing machine, and may be aptly termed a rotary machine in contradistinction to that type wherein covers are completely and 15 solely manipulated in a vertical plane with the bottles on which the covers are to be placed.

The primary object of my invention is to provide a bottle cover placing machine of 20 great capacity, wherein rotary vacuum means is employed for obtaining and manipulating a collapsed cover to open and shape the cover during the movement of the rotary means and convey the cover to a bottle or 25 similar receptacle.

Another object of my invention is to provide a bottle cover placing machine which obviates the necessity of using independently actuated grippers or fingers and the mechanism incident to such devices, all of which 30 must be operated in timed relation to the movement of a bottle and is necessarily comparatively slow in operation, besides being subject to cover imperfections and false 35 moves which may clog the machine or retard the cycle of manipulating a cover.

A further object of my invention is to provide a machine of the above type wherein the parts are constructed with a view of reducing 40 the cost of manufacture and at the same time retain the features by which simplicity of construction, durability, ease of assembling, safety of cover manipulation are secured. With such ends in view, my invention 45 resides in the novel construction to be hereinafter described and then claimed.

Reference will now be had to the drawings, wherein—

Figure 1 is a vertical sectional view of the 50 bottle cover placing machine, partly in elevation and partly broken away;

Fig. 2 is a horizontal sectional view of the machine taken on the line II—II of Fig. 1, and

55 Fig. 3 is a similar view taken on the line III—III of Fig. 1.

In the drawings, 1 denotes a base and mounted therein is the lower end of a tubular upright or pedestal 2 having a solid extension 3 at the upper end thereof. The upper 60 end of the base 1 has a holder 4 for a ball race 5 and on said ball race are anti-frictional balls 6 supporting the hub 7 of a horizontally disposed gear wheel 8. The gear wheel 8 has a hub extension 9, coupled as at 65 10, to the hub 11 of a rotary horizontally disposed head 12. The head 12 has a concentric recess 13 providing clearance for a cam 14, which has one hub portion thereof fixed to the upright extension 3, as at 15, and 70 another hub portion thereof extending into the hub 11.

The top of the rotary head 12 has a plurality of equally spaced and radially disposed grooves 16 and slidable in said grooves 75 are vacuum or suction members 17 having the inner ends thereof provided with depending rollers 18 extending into a cam groove 19 in the top of the cam 14, as best shown in Fig. 2. The outer ends of the suction members 17 are provided with vertically disposed suction heads 20 in communication with depending tubes 21 which have the lower ends thereof provided with flexible connections 22 to nipples 23, carried by the 80 hub 11 of the head 12. In the hub 11 is a ported bushing 24 having ports corresponding in number to the nipple 23 and the ports of said bushing are adapted to successively communicate with a segment slot 25 in the 85 tubular upright 2, said slot establishing communication between the upright and practically four bushing ports, at one time.

The lower end of the tubular upright 2 has a nipple 26 extending through the base 95 1 and connected by a conduit 27 to a vacuum pump 28. This vacuum pump or apparatus is of a conventional form and has the operating shaft 29 thereof coupled, as at 30, to the armature shaft 31 of an electric motor 32 or 100 other source of power.

The operating shaft 29 of the vacuum pump or apparatus 28 is also adapted for imparting a rotary movement to the head 12 and this is accomplished in the following 105 manner. The holder 4 of the base 1 has a bracket 33 and journaled in said bracket is a shaft 34 of a worm 35 meshing with the horizontally disposed gear wheel 8. The shaft 34 has a fixed clutch member 36 and 110 adapted to mesh therewith is an adjustable clutch member 37 slidable on the shaft 29,

but adapted to rotate therewith. The clutch members 36 and 37 constitute means for controlling the operation of the rotary head 12 relative to the vacuum pump or apparatus 28, and the mechanism for shifting the clutch member 37 will be hereinafter referred to in connection with a bottle conveyer.

The vacuum or suction members 17 are retained within the grooves 16 of the head 12 by a ring 38 secured to the head 12 and to the arms of a spider 39, said spider being connected as at 40 to a bearing sleeve 41 upon the solid extension 3 of the tubular upright 2. The spider 39 bears upon the upper end of the hub portion of the cam 14, as clearly shown in Fig. 1.

The rotary head 12 is provided with equally spaced radially disposed stationary cover holding arms 42 and these arms have the confronting sides thereof, at the outer ends, provided with notches 43 which are substantially V shaped in cross section.

At one side of the upright or pedestal 2 there is another pedestal 44 supporting a magazine 45 for collapsed bottle covers 46. These bottle covers are preferably of that character made of a durable paper cut and formed to provide a bottle cover that is open at both ends and somewhat frustconical shaped in elevation, the cover being designed to fit over a bottle, rest upon the breast of a bottle, and serve as a shield for the bottle particularly to exclude light and serve as a packer. The covers 46 are fed to one end of the magazine 45 by a follower 47 actuated by weights 48 connected to the follower by cables 49 trained over revolute sheaves 50. The magazine is positioned so that each suction member 17 may be projected into the open end of the magazine to obtain a cover by suction and remove the same to a position between the cover holding arms 42.

The upper end of the stationary upright extension 3 is provided with an overhanging arm 51 constituting a support for a fixed bearing shaft 52, which has the lower end thereof provided with a horizontally disposed fixed cam 53. Rotatable on the bearing shaft 52 above the cam 53, is a circular gripper head 54 having the hub 55 thereof provided with a gear wheel 56. This gear wheel is driven by a train of small gears 57 supported from the arm 51 and the train of gears is driven by a large horizontally disposed gear wheel 58 fixed upon the upper end of the bearing sleeve 41 to rotate in synchronism with the head 12 on the upright 2.

The gripper head 54 is provided with radially disposed slots 59 and pivoted upon said head at the outer ends of the slots, are gripping arms 60. The outer ends of the arms 60 have grippers 61 and the inner ends

thereof are connected by coiled retractile springs 62 adapted for opening the grippers 61. Between the inner ends of the gripping arms 60 and adapted for closing the grippers 61 are rollers 63 on the upper ends of pins 64 slidble in the radial slots 59 of the head 54. The lower ends of the pins 64 have rollers 65 engaging the periphery of the cam 53, and the rollers 65 are held normally in engagement with said cam by the retractile force of the springs 62 tending to close the inner ends of the arms 60 which impinge against the upper rollers 63. With the cam 53 held stationary and the gripper head rotated, it is apparent that the shape of the cam 53 determines the opening and closing of the grippers 61, and by reference to Fig. 2, it will be noted that the gripper head 54 is placed contiguous to the head 12 whereby the grippers 61 will be moved over the marginal edges of the head 12. The grippers 61 are adapted to close upon an opened cover held by the head 12 and transfer the cover to a bottle or similar receptacle, which may be manually placed to receive the cover or may be automatically placed in position by a bottle conveyer, a conventional form of which will now be described.

Below the gripper head 54 is a trough 66 provided with legs or suitable supports 67. In the trough 66 is an endless conveyer, preferably in the form of a sprocket chain 67 having seat members or cups 68 adapted to receive bottles 69. One of the sprocket wheels 70 over which the chain 67 is trained may be driven, as at 71, from the pump or apparatus shaft 29.

The side walls of the trough 67 are provided with buffer members 72 and 73, the latter being connected, as at 74, to an arm 75 pivoted to a bracket 76 on the side of the trough 66. The arm 75 may be connected to the bracket 76 by a coiled retractile spring 77 employed to hold the buffer 73 in the path of a bottle 79 whereby said buffer may be actuated by a bottle passing between said buffers. The arm 75 is connected by a link 78 to a fulcrum lever 79 carried by a bracket 80 projecting from the vacuum pump or apparatus 28. The fulcrum lever 79 is adapted for shifting the clutch member 37 into and out of engagement with the clutch member 36, similar to an ordinary clutch mechanism.

In the operation of the machine, a vacuum pump or apparatus 28 and the bottle conveyer are continuously operated and the operation of the suction head 12, as well as the gripper head 54, depends entirely upon whether a bottle or receptacle is in position or about to enter a position to receive a cover. Assuming a bottle 69 in one of the seats or cups 68 impinges against the buffers 72 and 73, the latter is actuated to throw in the clutch member 37 and permit of the worm 35 imparting a rotary movement to 130

the head 12. This head is rotated and as the cam 14 is held stationary, the suction members are reciprocated within the head 12 and the suction members 17 moved according to the contour of the groove 19 in the cam. By reference to Fig. 2, it will be noted that one of the suction members 17 has entered the magazine 45 and when the suction head 20 of the member is about to engage a cover, the slot 25 of the upright 2 establishes communication between said upright and the suction head 20 whereby an atmospheric reduction will cause the bottle cover 46 to adhere to the head 20 and permit of the member 17, when retracted, removing the bottle cover from the magazine into the notches 43 of the cover holding arms 42. The notches 43 are shaped to receive the folded edges of the cover 46 and while the head 12 is carrying the cover toward the gripper head 54, the cover is flexed in two directions to open the same. It will be remembered that the slot 25 establishes communication between the tubular upright 2 and more than one of the ports of the bushing 24, consequently an atmospheric reduction is maintained in the cover holding head 20 during practically a quarter revolution of the head 12. As the cover is carried from the magazine toward the gripper head 54, the suction member 17 is retracted to that extent as to concave the cover relative to the periphery of the head 12 and then convex the cover. The convex movement of the cover places the outer wall thereof in an open position, and then the concave movement of the cover places the inner wall of the cover in an open position. By this time the cover has reached the position opposite the gripper head 54 and as said head is rotated in timed relation to the head 12 and the opening and closing of the grippers 61 controlled by the cam 56, the grippers 61 are adapted to close in on the upper end of the cover and in gripping the cover tending to further open the same. This has been shown in Fig. 2 where the grippers 61 at the opening wheel have gripped the upper end of the cover, squeezing the walls together, and thereby holding the lower walls of the cover bowed and open. With the upper end of the cover held between the grippers 61 and the head 54 rotating, the cover is removed from between the arms 42 and transferred to a position above the bottle 69. The grippers 61 are automatically opened allowing the cover to descend on to the bottle 69.

During this operation of removing one cover from the magazine and transferring it to a bottle, other covers are being manipulated, and as shown, it is during the quarter revolution of the rotary head 12 that a bottle cover is opened. It is therefore apparent that the capacity of the machine may be materially increased by duplicating the

magazine 45 and the gripper head 54 in connection with that size of rotary head 12 shown, furthermore that this head may be made of such a diameter as to serve a plurality of magazines and gripper heads.

By referring to Fig. 2, it will be noted that the cam groove 19 has a contour which will shift the suction member 17, whereby a cover is first withdrawn from the magazine against the rounded ends of the cover holding arms 42. The cover is next drawn between the arms to cause the side edges of the cover to spring into engagement with the notches 43. Next, the cover is convexed and then concaved with the side edges of the cover held during both flexing actions. In gripping the upper end of the cover by the grippers 61, the side edges of the cover are practically removed from the notches 43 of the arms 42, as the cover tends to become more cylindrical and may be easily deposited upon a bottle.

My invention is not necessarily limited to the use of a bottle conveyer and the automatic control operation of the rotary head 12, although this automatic control of the head 12 will prevent covers from clogging the machine when a bottle is not in position. It is apparent however that should a cover miss a bottle, the conveyer will simply carry the same away. The bottles may be placed in position by hand, and while in the drawings there is illustrated a preferred embodiment of my invention, it is to be understood that the structural elements are susceptible to such variations and modifications as fall within the scope of the appended claims.

What I claim is:—

1. In a bottle cover manipulating machine, a magazine for collapsed covers, a rotary head, and means carried by said head adapted to remove a cover from said magazine to open said cover during the rotation of said rotary head.

2. In a bottle cover manipulating machine, a magazine for collapsed covers, a rotary head, and suction means carried by said head and adapted to remove the cover from said magazine and open said cover during a portion of the revolution of said head.

3. In a bottle cover manipulating machine, a magazine for collapsed covers, a rotary head, and reciprocable means carried by said head adapted to remove a cover from said magazine and flex it in two directions to open the cover.

4. In a bottle cover manipulating machine, a magazine for collapsed covers, and rotary and reciprocable suction means adapted to remove a cover from the magazine and flex it in two directions to open the cover.

5. A bottle cover manipulating machine embodying rotary and reciprocable suction

- means adapted to flex a collapsed cover in two directions to open the cover, and means for holding the cover during the flexing thereof.
5. 6. A cover placing machine embodying rotary and reciprocable suction means adapted to flex a collapsed cover in two directions to open the cover, means for holding the cover during the flexing thereof, and means adapted for gripping and removing the cover from said cover holding means.
10. 7. A cover manipulating machine comprising a magazine adapted for collapsed covers, a rotary head, arms about said head adapted for holding covers, and reciprocable suction means about said head adapted for removing covers from said magazine to positions between said arms, and flexing said covers while held by said arms to open the covers.
15. 8. A cover manipulating machine comprising a magazine adapted for collapsed covers, a rotary head, radial arms on said head adapted for holding covers by the edges thereof, and reciprocable suction means about said head adapted for removing covers from said magazine to positions between said arms and flexing said covers to concave and convex positions to separate the walls of the collapsed covers.
20. 9. In a cover manipulating machine, a magazine for collapsed covers, a plurality of arms adapted to successively hold covers, and reciprocable suction means between said arms adapted to successively shift covers from said magazine to said holding arms and open said covers while held thereby.
25. 10. In a cover manipulating machine, a magazine for collapsed covers, a plurality of arms adapted to successively hold covers, a plurality of suction members adapted to successively shift covers from said magazine to said holding arms and flex the covers while held thereby to separate the walls of the collapsed covers, and means adapted for gripping, removing and maintaining the covers open relative to said holding arms.
30. 11. In a bottle cover machine, a magazine for collapsed covers, a cover gripping device, and means for moving covers from said magazine to said device adapted to successively engage and flex a plurality of covers while being moved from said magazine to said device.
35. 12. In a bottle cover manipulating machine, a magazine for collapsed covers, a tubular upright, a source of suction in communication with said upright, a rotary head on said upright, and suction members on said head adapted to successively communicate with said tubular upright, remove covers from said magazine, and flex the covers to open the same.
40. 13. In a bottle cover manipulating machine, a tubular upright, means for simultaneously revolving and maintaining an atmospheric reduction in said upright, a head carried by said upright, a plurality of radially disposed suction members reciprocable on said head and adapted to communicate with said upright, and a stationary cam engaged by said suction members adapted to cause said members to reciprocate in timed relation to the rotation of said head.
45. 14. In a bottle cover placing machine, a suction head adapted to manipulate a cover, a source of suction for said head, means controlling the operation of said suction head, buffers between which a bottle is adapted to pass to actuate one of said buffers and receive a cover, and means actuated by one of said buffers to govern the suction head controlling means.
50. 15. In a bottle cover placing machine, a magazine for collapsed covers, a reciprocable suction member adapted to remove a cover from said magazine and swing in a horizontal plane to deliver said cover at a point remote from said magazine, and a rotary gripping device adapted to grip a cover held by said member.
55. In testimony whereof I affix my signature in the presence of two witnesses.
